UNITED STATES PATENT OFFICE.

JAMES E. MORTON, OF DALLAS, TEXAS.

STREET-INDICATOR FOR ELECTRIC CARS.

1,075,055.

Specification of Letters Patent.

Patented Oct. 7, 1913.

Application filed January 13, 1913. Serial No. 741,612.

To all whom it may concern:

Be it known that I, JAMES E. MORTON, a citizen of the United States, residing at Dallas, in the county of Dallas and State of Texas, have invented certain new and useful Improvements in Street-Indicators for Electric Cars, of which the following is a specification.

My invention relates to street indicators for electric cars, and it has for its object to mount within a street car a device that will indicate to the persons in the car the name of each cross-street as the car approaches the same.

It is a further object of the invention to provide a street indicating device for electric cars that will be entirely automatic in its operation, and which, when once installed will require no attention either from the motorman or conductor.

A still further object is to provide a device of the character described that will not operate when the car is backing up, and which will not require readjustment when a car which ordinarily runs upon one line in a city is transferred to some other line, as is frequently done.

The object of the invention stated specifically is to provide a street indicator for electric cars primarily comprising a plurality of ribbons having their extremities consecutively mounted upon drums carried by an upper and a lower shaft, the letters of the alphabet being printed in their proper succession upon each ribbon, and a mechanism being provided by which certain of these ribbons will be subjected to a certain amount of travel as the car approaches any cross street, the amount of travel impressed upon the ribbons being such as to cause the name of the street to appear through a window provided in the casing within which the device is mounted.

The object of the invention is finally to provide a device of the character described that will be strong, durable, simple and efficient and comparatively easy to construct and also one the various parts of which will not be likely to get out of working order.

With these and various other objects in view my invention has relation to certain novel features of the construction and operation, an example of which is described

in the following specification, and illustrated 55 in the accompanying drawings, wherein:

Figure 1 is a view in side elevation showing the upper portion of a street car equipped with the herein described street indicating device, this view also showing in 60 side elevation one of the devices which are to be mounted upon the trolley wire some distance from each street for the purpose of actuating the indicator mechanism and thereby causing the street name to appear in 65 the aforesaid window. Fig. 2 is a front view of the indicator casing showing the window in said casing through which the name of a street may be read as the car approaches said street. Fig. 3 is a view 70 showing the device in front elevation with the front wall of the casing removed. Fig.

4 is a transverse sectional view taken upon the line X—X of Fig. 3. Fig. 5 is a detail sectional view showing one of the drums 75 adapted to carry the lower end portion of a correlated ribbon carrying the letters of the alphabet. Fig. 6 is an end view of one

of the devices which are to be mounted upon the trolley wire some distance from each street, said device being the primary 80 actuating means by which the mechanism within the street car is caused to spell the name of the street adjacent to which said device is mounted. Fig. 7 is a sectional 85 view of the same device, the section being taken upon the line Y—Y of Fig. 6. Fig. 8 is a view showing in rear elevation a device mounted upon the upper portion of a trolley pole, the primary members of said 90 device being a plurality of toothed wheels which are adapted to respectively engage a plurality of racks carried by the devices illustrated in Figs. 6 and 7. Fig. 9 is a view showing the same device in sectional 95 elevation, the section being taken upon the line Z—Z of Fig. 8. Fig. 10 is a longitudinal sectional view of a dash pot embodied in the device illustrated in Figs. 8 and 9.

Fig. 11 is a detail front view of a valve 100 provided for the dash pot plunger. Fig. 12 is a detail sectional view of an elbow of pipe, through which pipe certain wires are carried upon small rollers. Fig. 13 is an end view of said elbow.

Referring now more particularly to the

drawings, wherein like reference characters

designate similar parts in all the figures, the

numeral 1 denotes a street car which is provided with the usual trolley pole 2 inclined upwardly and rearwardly, and provided at its free end with the trolley wheel 3 engaging the trolley wire 4.

The invention comprises three primary members one of which is to be mounted upon the trolley wire, another upon the upper portion of the trolley pole, and the third 10 to be mounted within the street car upon the front wall thereof. The member last specified will be first described. The mechanism of this member is contained within a casing 5, provided in its front wall with a horizontally elongated window 5^a. The casing 5 is provided with a circular aperture at the center of its top wall, which wall will preferably be inclined upwardly toward said aperture at each side thereof. Within 15 the casing, there are mounted two vertically spaced horizontal shafts, the upper of which is designated by the numeral 6 and the lower by the numeral 7. The extremities of said shafts are rigidly mounted in bracket 20 members 8 carried by the side walls of the casing. The upper shaft 6 carries a plurality of rotatably mounted drums 9, and an equal number of rotatably mounted drums 10 are carried by the lower shaft 7. The 25 drums 9 are paired with the drums 10 to carry the end portions of a plurality of elongated ribbons 11, the upper and lower extremities of each ribbon being respectively secured to the correlated drums 9 and 10. Each ribbon 11 carries the letters of the 30 alphabet arranged in their proper succession, this succession being made to commence at that extremity of the ribbon carried by one of the drums 9 and being ended upon that extremity of the ribbon carried 35 by one of the drums 10. It is thus apparent that when any ribbon is subjected to travel in an upward direction, the letters of the alphabet carried by said ribbon appear successively in the window 5^a, the succession 40 extending from A to Z.

Each of the drums 10 has a central cylindrical aperture 12 extending into one of its sides, and within said aperture there is 45 mounted a coil spring 13, one end of which is rigidly secured to the shaft 7 and the other end rigidly secured to the drum. The coiled springs 13 impress upon the drums 10 a rotative impulse, tending to wind the 50 ribbons 11 upon the correlated drums 10. When the maximum amount of any ribbon has been wound upon the correlated drum 10, leaving the correlated drum 9 substantially empty, such a ribbon will appear as 55 is shown at the right and left hand sides in Fig. 3, an unprinted space upon the upper end portions of the ribbons being made to appear opposite the window 5^a. The torsion of the springs 13 may be sufficiently 60 overcome to permit any of the letters car-

ried by the ribbons 11 to appear before the window 5^a. The drums 9 are held in a proper spaced relation by a plurality of collars 14 loosely carried by the shaft 6, and a plurality of collars 15 similarly serve to hold the drums 10 in a proper spaced relation. Each of the drums 9 carries integrally a supplementary drum 16, the drums 16 being somewhat smaller in diameter than the drums 9, and being of a considerably 70 smaller width. To the face of each supplementary drum 16 there is secured the extremities of a wire 17, each of the wires 17 being extended upwardly and over a pulley 18, which pulleys are mounted loose upon a plurality of pins 19^a forwardly projecting from a horizontal bar 19 having its extremities respectively mounted upon the end walls of the casing 5. When one of the wires 17 is being unwound from the correlated drum 16, a ribbon 11 will be winding upon the drum 9 with which said drum 16 is correlated, and vice versa. When a maximum portion of any ribbon 11 is wound upon a drum 10, the drum 16 which is correlated with the drum 9 carrying the other extremity of said ribbon will have coiled upon it a sufficient amount of the wire 17 to cause a maximum portion of said ribbon to wind upon the correlated drum 9 while the coils of wire 17 are being unwound from the drum 16.

It is obvious from the foregoing description that by drawing off a certain amount of wire 17 from one of the drums 16, any letter carried by the correlated ribbon 11 may be made to appear before the window 5^a, and by thus making the proper letters appear upon a plurality of the ribbons 11, any street name can be made to appear in the window 100 5^a. The wires 17 after passing over the small pulleys 18 are extended at an upward inclination toward the central aperture in the top of the casing 5. Within said aperture are mounted a plurality of parallel 105 horizontal spindles 20, each carrying a plurality of small loosely mounted pulleys 21. The wires 17 after each passing over one of the pulleys 21 are extended upwardly through the central aperture in the top of 110 the casing. In the accompanying drawings, the wires 17 are twelve in number, and three of the corresponding pulleys 21 are mounted upon each of the spindles which are four in number. A short space above the spindles 115 20 there are mounted an equal number of spindles 22 horizontal in position and transverse in direction with the spindles 20. Upon each spindle 22 there are mounted three small pulleys 23 which serve to guide 120 the wires 17 as they extend in an upward direction.

A pipe 24 communicates at its lower end with the central aperture in the top of the casing 5 and at its upper end said pipe 130

passes through the roof of the car 1. The upper end of the pipe 24 communicates through an elbow 25 with a horizontal pipe 26 longitudinally mounted upon the roof of the car and extending to the foot of the trolley pole 2. The pipe 26 communicates at its rear end with a pipe 27 secured to the trolley pole by a plurality of brackets 28 and terminating in an open end some distance from the top of the trolley pole. The wires 17 are made to pass through the pipes 24, 25, 26 and 27, being supported wherever necessary in said pipes by sets of pulleys 21 and 23 such as have been already described. In order to more clearly illustrate the manner of supporting the wires 17 within said pipes, the detail views (Fig. 12 and Fig. 13) showing the wires passing through the elbow 25 are furnished in the accompanying drawings.

A description will now be given of a device which is to be mounted upon the upper extremity of the trolley pole 2, said device forming one of the three primary members which constitute the invention. An elongated plate 29 is mounted centrally and transversely above the upper extremity of the trolley pole, the central portion of said plate lying directly above the trolley pole being horizontal, and the two lateral portions being inclined downwardly at the same gradual inclination. The plate 29 is held in a rigid relation to the trolley pole by a pair of bracket members 30 having the nature of bars each bolted or otherwise secured at its outer end beneath one of the inclined side portions of the plate 29 and the two having their inner end portions clamping the trolley pole between them. The extremities of the plate 29 are turned upwardly as indicated at 30^a in Fig. 8 of the drawings. Upon each of the inclined portions of the plate 29, there is mounted an equal number of U shaped brackets 31, the total number of these brackets being equal to the total number of wires 17. Any suitable means may be employed to secure the brackets 31 in a rigid relation to the plate 29. The bottom portions of the brackets 31 will preferably be given the same inclination as is provided to the lateral portions of the plate 29, as is clearly shown in Fig. 8 of the drawings.

Within each U shaped bracket 31, there is mounted a toothed wheel, the construction of which will now be described in detail. Each of said wheels is primarily formed of five metal disks respectively designated by the numerals 32, 32^a, 33 and 33^a. The disks 32 and 32^a have substantially the same diameter. The disk 33^a has a somewhat greater diameter and the two disks 33 have a considerably greater diameter than the disks 32 and 32^a. These disks are concentrically riveted or bolted together as in-

dicated at 34, the disk 32 being clamped between the members 33, and the disk 32^a, which will preferably have a somewhat lesser width than the disk 32, being clamped between one of the members 33 and the member 33^a.

From the above description and from the drawings, it will be seen that an annular chamber is formed between the peripheral portions of the disks 33 of each wheel. In this chamber there are pivotally mounted a plurality of equidistantly spaced triangular teeth 35, the pivot pins 36 supporting said teeth having their extremities mounted in the disks 33. In the position normally occupied by the teeth 35, one edge of each tooth will be substantially radial in position, the pivotal point of the tooth being located at the apex formed by the juncture of the other two edges. When the teeth 35 are in their normal position just described, a considerable space intervenes between each tooth and the circular face of the disk 32. Each tooth is prevented under normal conditions from swinging about its pivotal support by securing one extremity of a curved leaf spring 39 to the tooth adjacent to said pivotal support and causing the other end of said spring to bear upon the face of the disk 32. A lug 37 projects from the juncture of the two edges of each tooth which form a right angle and this lug through engagement with a pin 38 having its extremities mounted in the disks 33 respectively, prevents the correlated tooth from swinging outwardly about its pivotal support. It will thus be plainly seen that the teeth are adapted to resist any force acting perpendicularly against their radial faces, but if a tangentially acting force is applied to the inclined edge of any tooth, said tooth may swing about its pivotal support until the lug 37 contacts with the face of the disk 32, provided that the tangential force is sufficient to overcome the tension of the spring 39. Each of the wheels just described is mounted fast upon a pintle 39^a having its extremities journaled in the correlated U shaped bracket 31.

It has been already stated that the wires 17 each have one extremity secured to the face of one of the drums 16, and it has been also explained that the wheels just described are equal in number to the wires 17. The other extremities of the wires 17 are respectively secured to the rims of the disks 32^a, which disks form drums upon which the wires may be wound. The wires are secured to the disks 32^a in such a manner that a force acting tangentially against the radial faces of the teeth 35 will tend to wind said wires upon said disks 32^a. The wires 17 extend vertically downward from the disks 32^a and are passed over small pulleys 40 rotatably mounted upon pins 41 upon

projecting perpendicularly from a horizontal bar 42 which has its ends bent at right angles in a rearward direction and bolted or otherwise secured to the upturned ends 5 30^a of the bar 29. From the center of the bar 42, two bars 44 are extended divergently downward, the lower extremities of the said bars being provided with feet which are secured to a horizontal central portion of 10 a bar 45 which has its lateral portions inclined upwardly and bolted or otherwise secured to the upturned members 30^a. From each of the bars 44, there projects an equal number of pins 47 serving to rotatably support small pulleys 46. The wires 17 after passing over the pulleys 40 are extended at a downward inclination to the pulleys 46 passing over the same as is most clearly shown in Fig. 8. Upon the lower extremities of 20 the bars 44 a pair of opposite bearings 48 are mounted which serve to rotatably support the extremities of a spindle 49 carrying a plurality of small pulleys 50 equal in number to the wires 17. The wires 17 after 25 passing over the pulleys 46 are extended vertically downward to the pulleys 50 and after passing over the latter set of pulleys are extended into the open upper end of the pipe 27. The means for supporting said 30 wires during their passage through the pipe 27 and other pipes connected therewith has already been described. It is to be understood that when any wheel mounted in the brackets 31 is subjected to a sufficient angular displacement to produce a rotation equal to the distance between two teeth, the resulting displacement communicated to the correlated wire 17 will cause the correlated ribbon 11 to undergo a displacement 35 equal to the distance between two of the letters carried by said ribbon, causing any letter to be replaced by the next successive letter.

It must at this point be understood that 45 when the device surmounted upon a trolley pole encounters one of the plurality of the devices to be mounted upon the trolley wire, certain of the wheels carrying the teeth 35 will be subjected to such a rotation as will 50 cause to appear in the window 5^a the name of the street next adjacent to the device upon the trolley wire which was encountered by the device upon the trolley pole. Unless some restraining means is provided, the 55 action of the coiled springs 13 would tend to wind the ribbons 11 upon the drums 10 as soon as the device carried by the trolley pole is released from the device carried by the trolley wire. In order that the name 60 of the street may continue to appear before the window 5^a until the car has passed said street, it is necessary to temporarily hold the wheels carrying the teeth 35 against a reverse rotation after they have been subjected to angular displacement. The means

provided for this purpose comprises a metal bar having its two extremities pivoted upon the rearwardly projecting extremities 51 of the bar 42. Said bar comprises two vertical side portions 52 and two similar stepped center portions 53, the steps of which are adapted to engage above the radial edges of the teeth 35. The stepped portion of the dog or pawl formed by the bar comprising the members 52 and 53 is normally held in 70 engagement with the teeth of the wheels 35 by a coiled spring 54, having one of its extremities secured to a bar 59, projecting forwardly from beneath the center of the member 53 and bent downwardly adjacent to its point of connection with said member 53. The other extremity of the spring 54 is secured to a bar 55 transversely extending between the two uppermost brackets 31 which are surmounted upon the plate 29. Between the said two uppermost U shaped brackets 31, there is mounted a dash pot 56 which rests upon the horizontal center portion of the plate 29, the axis of said dash pot being parallel with the trolley wire. The plunger 57 of the dash pot projects through the rear wall thereof and is connected by a pitman 58 with the lower extremity of the bar 59. It is thus apparent that when the bar comprising the members 52 and 53 is displaced to the position shown in dash lines in Fig. 9, in which position said bar is disengaged from the teeth 35, the plunger 59^a of the dash pot will be displaced from the forward to the rear extremity of the cylinder 56. The plunger head 59^a is provided with a number of apertures 59^b which are closed by spring pressed valves 59^c mounted upon the forward face of said plunger head, as clearly 90 shown in Fig. 11. When the plunger head is displaced from the forward to the rear end of the cylinder 56, the valves 59^c will automatically open to permit the air in the 95 front portion of the cylinder to pass to the rear portion thereof. Owing to the action 100 of the coiled spring 54, the plunger will gradually return to its normal position to the front end of the cylinder (shown in Fig. 10), the air being permitted to escape 105 through the plunger by way of a plurality of very small apertures 59^b transversely passing through the plunger. These apertures are so small that the air pressure in front of the plunger 59^a will for some time 110 resist the action of the spring 54 so that the plunger will move forwardly very slowly. 115 A description will now be given of the means provided for releasing the teeth 35 from the pawl 52, 53 after a street car has 120 passed a street, the name of which is being displayed through the window 5^a. Upon the center of the member 53 between the stepped side portions thereof, there is 125 mounted a vertical trip bar 60 the same be- 130

ing provided at its lower end with a foot which is secured to the member 53. At the point in the path of the car where it is desired to release the wheels carrying the 5 teeth 35, a tripping bracket 61 is secured to the neck of one of the insulating members 62, commonly employed to attach the brace wires 63 to the trolley wire. The relation of the members 60 and 61 to each other is 10 such that the upper extremity of the former member will contact with the latter member upon reaching the same. As a result, the dog formed by the members 52 and 53 will be disengaged from the teeth 35 and will be 15 thrown into the position illustrated in dash lines in Fig. 9. In undergoing this displacement, the dog 52, 53 will communicate a displacement through the members 57, 58 and 59 to the plunger 59^a of the dash pot 56, 20 displacing said plunger from the forward to the rear end of the dash pot cylinder. The fluid preferably air contained within the dash pot will gradually pass through the small apertures 59^b thus permitting the 25 plunger 59^a to return to its normal rear-most position due to the action of the spring 54. However, before the dog 52, 53 again engages the teeth 35, the wheels carrying said teeth will have been rotated to their 30 normal position due to the torsion of the springs 13 acting through the wires 17. As soon, therefore, as the member 61 is engaged by the tripping bar 60, the ribbons which carry the letters forming the name of 35 a street displayed through the window 5^a will be simultaneously subjected to a downward displacement and a blank portion of each ribbon will appear before said window.

A description will now be given of the 40 third primary member comprising the street car indicator, this member being mounted upon the trolley wire, as indicated in Figs. 6 and 7 of the drawings. An elongated metal plate 64 is mounted lengthwise upon 45 the trolley wire, the middle portion of said plate being secured to the wire by suitable fastening devices indicated by the numeral 68. At each side of the horizontal central portion of the plate to which portion said 50 trolley wire is secured, a plurality of successive steps are formed in the plate, the two lateral stepped portions being symmetrical in form. The total number of steps provided to the plate 64 will be equal to the 55 total number of wires 17. In order to hold the plate 64 steady in its proper relation to the trolley, there may be centrally mounted upon said plate a bracket member 65 to which bracket member may be secured 60 the brace wires 63 which extend to the trolley pole. As a still further means to hold the plate 64 in its proper position, a pair of brace wires 63 may be extended from the lateral edges of the plate 64 to each wire 65, 63 as is clearly shown in Fig. 6 of the draw-

ings. To the under face of the plate 64, there are secured a number of racks of teeth, said racks being designated by the numeral 67 and being each formed of a bar of metal, so bent as to give the proper form to the teeth. Each tooth will have one vertical and one inclined face and the teeth of every rack will be so spaced and proportioned that the wheels carrying the teeth 65 may roll upon said rack, the racks serving to communicate a constant rotation to the wheels during engagement. It is to be understood that the number of racks 67 which will be mounted upon any plate 64 will be equal in number to the number of letters in the name of the street desired to be shown before the window 5^a in the casing 5. Also the number of teeth in each rack will be just sufficient to bring the desired letters before the window 5^a. 75 80 85

Referring to the drawings, it will be seen that the name displayed through the window 5^a is "Clyde St." Since this name is formed by seven letters, there are shown seven racks of teeth mounted upon the plate 64. Referring to Fig. 7 of the drawings, it will be seen that the lowest rack contains three teeth thus being adapted to bring the third letter of the alphabet C before the window 5^a. Owing to the large number of teeth contained in the two next highest pairs of racks, these racks are not shown complete. It is to be understood, however, that the second highest rack will contain twelve teeth and the third highest rack twenty-five teeth thus 90 95 100 respectively producing before the window 5^a the twelfth and twenty-fifth letters of the alphabet namely L and Y. The uppermost rack shown in Fig. 7 comprises four teeth and will therefore produce the letter D before the window 5^a. It is thus seen how the consecutive letters CLYD are brought before the window and it will be readily understood how the remaining letters E and ST will be made to appear. 105 110

It is to be understood that the devices comprising the stepped plates 64 and teeth 67 are to be mounted at the approach to every street at which the car makes a stop. Thus as the car approaches each cross 115 street the name of such street will appear in the window 5^a. For every device comprising parts 64 and 67 that is mounted upon the trolley wire, there will also be mounted upon the trolley wire one of the tripping 120 brackets 61, these brackets being mounted just beyond the streets, the names of which are made to appear in the window 5^a.

The indicator above described and illustrated in the accompanying drawings is 125 adapted to display a street name containing as many as twelve letters. It will of course be understood however that a sufficient number of the ribbons 11, wires 17 and wheels carrying the teeth 35 may be employed to 130

cause any street name to be displayed irrespective of the number of letters in the name.

The invention is presented as including all such changes and modifications as properly come within the scope of the following claims.

What I claim is:

1. In a street indicator for electric cars, the combination with a casing mounted within a car and provided with a window, of a ribbon contained in said casing and adapted to travel longitudinally before the window, a plurality of letters being equidistantly carried by the ribbon, each of which letters is singly visible through the window in a certain position of the ribbon, a wheel rotatably mounted upon the upper extremity of the trolley pole of the car, a device mounted upon the trolley wire, entering into engagement with said wheel as the car passes beneath said device, and subjecting the wheel to a certain amount of rotation, a means establishing a relation between said wheel and said ribbon such that the said rotation of the wheel actuates the ribbon through a certain amount of travel, and causes a certain letter to appear before the window, a spring opposing the travel of the ribbon actuated by said wheel, and tending to normally maintain the ribbon in a position such as to expose a blank portion of its surface through said window, a dog normally engaging the wheel serving to temporarily hold the wheel in a displaced position, a tripping arm carried by said dog, and means mounted upon the trolley wire for engaging said tripping arm and temporarily releasing the dog from engagement with the wheel.
2. In a street indicator for electric cars, the combination with a casing mounted within a car and provided with a window, of a ribbon contained in said casing and adapted to travel longitudinally before the window, a plurality of letters being equidistantly carried by the ribbon, each of which letters is singly visible through the window in a certain position of the ribbon, a toothed wheel rotatably mounted upon the upper extremity of the trolley pole of the car, a rack of teeth mounted upon the trolley wire and adapted to be engaged by the teeth of said wheel as the car passes beneath said rack, thereby subjecting said wheel to a certain amount of rotation, means of establishing a relation between said wheel and said ribbon such that the said rotation of the wheel actuates the ribbon through a certain amount of travel, and causes a certain letter to appear before the window, a spring opposing the travel of the ribbon actuated by said wheel, and tending to normally maintain the ribbon in a position such as to expose a blank portion of its surface through said

window, a dog normally engaging said wheel serving to temporarily hold the wheel in a displaced position, a tripping arm carried by said dog, and means mounted upon the trolley wire for engaging said tripping arm and temporarily releasing the dog from engagement with the wheel.

3. In a street indicator for electric cars, the combination with a casing mounted within a car and provided with a window, of a ribbon contained in said casing and adapted to travel longitudinally before the window, a plurality of letters being equidistantly carried by the ribbon, each of which letters is singly visible through the window in a certain position of the ribbon, a pair of drums upon which the ribbon's end portions are respectively carried, a spring acting upon one of said drums, impressing upon it a tendency to wind up the ribbon, a supplementary drum correlated with the other drum first mentioned, a wheel rotatably mounted upon the upper extremity of the trolley pole of the car, a supplementary drum rigidly carried by said wheel, a wire having one extremity secured to the last named supplementary drum and the other extremity to the first named supplementary drum within said casing, a device mounted upon the trolley wire, entering into engagement with said wheel as the car passes beneath said device, and subjecting the wheel to a certain amount of rotation, a dog normally engaging the wheel serving to temporarily hold the wheel in a displaced position of rotation, a tripping arm carried by said dog, and means mounted upon the trolley wire for engaging said tripping arm and temporarily releasing the dog from engagement with the wheel.

4. In a street indicator for electric cars, the combination with a casing mounted within a car and provided with a window, of a plurality of ribbons contained in said casing and adapted to travel longitudinally before the window, a plurality of letters being equidistantly carried by each ribbon, the letters carried by any ribbon being singly visible through the window in a certain position of said ribbon, a plurality of wheels rotatably mounted upon the upper extremity of the trolley pole of the car, a device mounted upon the trolley wire, entering into engagement with certain of said wheels as the car passes beneath said device, and subjecting the wheel to various amounts of rotation, means establishing a relation between each wheel and one of said ribbons, such that the rotation of the wheel actuates the correlated ribbon through a certain amount of travel and causes a certain letter to appear before the window, springs opposing the travel of the ribbons actuated by said wheels, and tending to normally maintain all of the ribbons in a position such as to expose a blank

portion of their surfaces through the window, a dog normally engaging the wheels, serving to temporarily hold the wheels in a displaced position of rotation, a tripping arm carried by said dog, and means mounted upon the trolley wire for engaging said tripping arm and temporarily releasing the dog from engagement with the wheels.

5. In a street indicator for electric cars, the combination with a casing mounted within a car and provided with a window, of a plurality of ribbons mounted within said casing and adapted to travel longitudinally before said window, a plurality of letters being equidistantly carried by each ribbon, and each of the letters carried by any ribbon, being singly visible through the window in a certain position of said ribbon, a plurality of toothed wheels rotatably mounted upon 10 the upper extremity of the trolley pole of the car, a plurality of toothed racks mounted upon the trolley wire and adapted to be engaged by certain of said wheels, as the car passes beneath the said device and therefore subject such wheels to a certain amount 15 of rotation, means establishing a relation between each wheel and one of said ribbons such that the said rotation of the wheel

actuates the correlated ribbon through a certain amount of travel causing a certain letter to appear before the window, a spring opposing the travel of each ribbon produced by said rotation of the correlated wheel, and tending to normally maintain the correlated ribbon in a position such as to expose a blank portion of its surface to the window, a dog normally engaging the teeth of the wheels serving to temporarily hold the wheels in a displaced position to which they are brought through engagement with said racks of teeth, a tripping arm carried by the said dog, means mounted upon the trolley wire for engaging said tripping arm and temporarily releasing the dog from engagement with the toothed wheels, and means for producing a gradual displacement of the dog from its inoperative to its operative position after any displacement from the wheels.

In testimony whereof I have signed my name to this specification in the presence of two subscribing witnesses.

JAMES E. MORTON.
